PAGE 2

FIG. 3.

FIG. 4.

FIG. 1 is a rear perspective view taken from the top and left side of a separator hood for a combine embodying my new design;

FIG. 2 is an elevational view taken from the right side thereof;

FIG. 3 is a rear elevational view thereof; and

FIG. 4 is a sectional view thereof to a larger scale, taken on a horizontal plane through the line 4—4 of FIG. 3, the front being substantially open.

I claim:

The ornamental design for a separator hood for a combine, as shown and described.
